CHAIN PIPE COVER

Edward L. Krogstad and George B. Lockwood,
Staten Island, N. Y., assignors to Lockstad Com-
pany, Wilmington, Del., a corporation of Dela-
ware

Application May 17, 1950, Serial No. 162,498

2 Claims. (Cl. 114—180)

1

This invention relates to a water-tight cover for sealing the chain pipe or spill pipe to the chain locker on a ship.

Unless the chain pipe is sealed, the chain locker is likely to be flooded when the ship encounters rough seas. When the chain locker is flooded, water finds its way into the upper and lower forward peak causing damage to stores and equipment. These store rooms together with the chain locker have a capacity for tons of water that cause the ship to plow under with consequent loss of time, waste of fuel oil and increase in the operating expenses of the trip.

It is an object of this invention to provide an improved water-tight seal for closing the chain pipe, and particularly to provide a simple and economical seal that can be applied quickly and conveniently without any alteration of or attachments to the structure of the ship, and that can be removed with the same facility when a ship approaches port and it is desirable to have the anchors free. It is also an object of the invention to avoid the use of bolts, the threads of which may become damaged and unusable.

Other objects, features and advantages of the invention will appear or be pointed out as the description proceeds.

In the drawing, forming a part hereof, in which like reference characters indicate corresponding parts in all the views,

Figure 1 is a top plan view of a chain pipe cover embodying this invention;

Figure 2 is a bottom plan view of the chain pipe cover shown in Figure 1;

Figure 3 is a sectional view taken on the line 3—3 of Figure 1 and showing the cover in place on a chain pipe with the anchor chain holding the cover in position;

Figure 4 is a fragmentary top plan view showing a clasp for holding portions of the cover clamped together;

Figure 5 is a fragmentary elevation showing the structure by which the opposite halves of the cover are pivotally connected at their rearward ends; and

Figure 6 is a perspective view showing the cover in use.

The chain pipe cover of this invention is made in two halves comprising a right-hand plate 10 and a left-hand plate 11. The plates 10 and 11 have confronting faces that come together along a line 13, but there are complementary recesses 16 and 17 extending along a portion of the length of the confronting faces; and these recesses 16

and 17 form a slot 18 when the two halves of the chain pipe cover are in assembled relation with one another.

The slot 18 has a width equal to the width of the respective chain links and the length of the slot 18 is slightly greater than the outside dimension of a chain link measured along the minor axis of the link. This extra length of the slot 18, in excess of the minor axis, permits the chain link 20 to occupy a sloping position in the slot 18, as shown in Figure 3. When a link 20 of a stud-link chain is located in the slot 18 and in the position illustrated, it substantially fills the slot and prevents leakage of water through the slot 18 into a chain pipe 21 located below the cover 9.

The cover 9 has a frame or ring 23 extending downward from its bottom face, and each half of the cover is connected with the corresponding half of the ring 23. There is a gasket 25, preferably made of rubber or other soft sealing material, connected to the bottom face of the cover 9 immediately outside of the ring 23. This gasket, as well as the ring 23, are divided along the same line 13 as the halves of the cover so as not to interfere with the separation of the plates 10 and 11.

The gasket 25 rests upon an annular lip 27 at the upper end of the chain pipe 21. The cover 9 is held against lateral displacement by having the ring 23 deeper than the gaskets 25 so that the ring 23 extends down beyond the upper end of the lip 27. The outside diameter of the ring 23 is substantially smaller than the inside diameter of the opening that is surrounded by the lip 27, but not enough smaller to let the cover shift laterally into a position where any arc of the lip is no longer covered by the gasket 25.

When the cover 9 is held down firmly against the lip 27, the gasket 25 provides a seal that prevents water from flowing into the chain pipe around the lip 27. The ring 23 is merely representative of either a frame or other abutment extending down within the lip 27 for preventing transverse displacement of the cover on the chain pipe, and it will be evident that a plurality of disconnected abutments can be used in place of the ring. In the preferred construction, however, the ring 23 extends without interruption along the entire inner face of the gasket 25 and thus provides protection for the gasket.

Figure 2 is a bottom view of the cover 9 and shows bars or ribs 31, 32 extending along the underside of the plates 10 and 11, respectively, 55 parallel to the confronting faces of the plates.

and located close to the edges of the slot 18. These ribs are integral with the plates 10 and 11, and may be welded to the plates or cast integral with the plates when the latter are made by casting. The ribs 31, 32 provide additional strength and prevent the plates from bending when they are pressed down against the end of the chain pipe while in use.

The plates 10 and 11 are made so that they can be hinged together at their rearward ends, but with a hinge connection that can be easily taken apart when the plates are removed from the end of the chain pipe. In the construction illustrated, a button or stud 35 extends upward from the plate 11, and there is a bracket or extension 36, of the plate 10, with a socket that fits over the stud 35. When the plates are assembled with the stud 35 engaged in the socket of the bracket 36, the plates are pivotally connected for angular movement about an axis that is normal to the top faces of the plates.

At their forward ends, the plates 10 and 11 are clamped together by a link 38 which is connected with a handle 39 by a pivot 40. The handle 39 is connected with the plate 10 of the cover, by a pin 42 extending through a bracket at the end of the plate. The link 38 engages a hook 43 that projects from the plate 11, and that is integral with the plate 11.

The dimensions of the parts are proportioned so that the handle 39 draws the link 38 against the hook 43 and tightly clamps the plates 10 and 11 against the chain link by the time that the handle 39 has moved into line with the link 38. The handle 39 is capable of moving slightly further in a counterclockwise direction so as to shift the pivot 40 to the right of the line along which the link 38 exerts its clamping pressure. This relieves the clamping pressure slightly but has the advantage of utilizing the pressure to hold the handle 39 in clamping position. In order to release the plates 10 and 11, the handle 39 is turned angularly about the pin 42 in a clockwise direction until the link 38 has moved far enough to swing clear of the hook 43.

Figure 6 shows the plates clamped together by the link 38 engaged over the hook 43. The cover is held down firmly against the chain pipe by a chain link 45 which has its lower end in contact with the plates 10 and 11 of the cover, as shown in elevation in Figure 3. The lower chain link 20 is clamped in the slot between the cover plates 10 and 11.

When the cover is to be put in place for sealing the chain pipe at the beginning of a voyage, the anchors are first hoisted tight to the ship's side and secured with devils claw and turnbuckle. The link of the chain which is to extend through the cover 9, that is, the link 20 in Figures 3 and 6, is then marked. The anchor chain is backed off about one length by means of the chain winch so as to conveniently install the cover 9 in place around the link 20 and over the upper end of the chain pipe 21 which leads to the chain locker.

The two plates 10 and 11 of the cover are hinged together by placing the bracket 36 over the stud 35 and the plates are clamped together, with the marked link 20 within the slot 18, by operating the handle 39. The anchor chain is then pulled tight again by the winch so that the weight of the link 45, and the weight of the other links hanging in the chain pipe from the link 20, hold the cover in place with enough downward thrust to maintain a water-tight joint between the lip 27 of the chain pipe and the plates of the cover.

The chain pipe 21 shown in the drawing has the lip 27 at its upper end at a level slightly above a deck 46. In actual practice the section of the deck through which the chain pipe opens is obstructed by adjoining structure, such as the frames for supporting the anchor winches, and there is very little space for swinging the plates of the cover into or out of position. It is a distinct advantage of this invention that the cover plates 10 and 11 can be removed, and replaced without swinging them angularly for any substantial distance about their hinged connection.

The construction illustrated with the slot 18 for the chain links, is intended for chains having stud links with which the stud portion of the clamped link prevents the flow of water through the center portion of the slot 18. When the cover is made for anchor chains having open links, the slot 18 is not used and each of the plates 10 and 11 is made with two spaced recesses that cooperate to form substantially circular openings of a cross section to fit around the opposite sides of the link which is clamped between the plates.

Various changes and modifications in the illustrated construction can be made without departing from the invention as defined in the claims.

We claim as our invention:

1. A chain pipe cover for closing the upper end of a chain pipe that leads to a chain locker of a ship and through which an anchor chain passes, said cover including two plates, each of which is adapted to cover substantially one-half of the open end of the chain pipe, complementary hinge elements on the respective plates connecting the plates together for angular movement with respect to one another about an axis normal to the top surfaces of the plates, clamping means that hold the plates together at their forward ends with a link of an anchor chain clamped between the plates, abutment means extending downward from the plates, the effective diameter of said abutment means being somewhat less than the inside diameter of the entrance to the chain pipe with which the cover is intended to be used, and a gasket connected to the underside of each plate and located immediately outside of said abutment means.

2. A chain pipe cover for closing the upper end of a chain pipe that leads to a chain locker of a ship and through which an anchor chain passes, said cover including two halves, each of which comprises a plate having a downwardly extending flange of an effective radius substantially less than the effective inside radius of a chain pipe with which the cover is intended to be used, a stud extending upward from one plate of the cover, a bracket extending from the other plate of the cover and having a socket into which the stud of the first plate extends to provide a hinged connection between the plates at their rearward ends, a clamping device at the forward ends of the plates including a hook on one of the plates, a handle pivotally connected with the other plate and carrying a link that engages the hook on the first mentioned plate to pull them together, the parts being so proportioned that the handle moves beyond the center line of the pull and is held in place by the pressure of the link against the hook, said plates having confronting faces that meet along a center line of the cover, and said confronting faces having recesses therein for receiving a link of an anchor chain, and ribs extending downward from the bottom faces of the plates substantially parallel to the confronting faces and at a location adjacent the inner

edges of the recesses for bracing the plates against bending along said confronting faces.
